UNITED STATES PATENT OFFICE

162,088

WOVEN RIBBON HAT

Samuel Scheuer, Mount Vernon, N. Y.

Application May 10, 1950, Serial No. 9,850

Term of patent 7 years

(Cl. D3—13)

To all whom it may concern:

Be it known that I, Samuel Scheuer, a citizen of the United States, residing at Mount Vernon, in the county of Westchester and State of New York, have invented a new, original, and ornamental Design for Woven Ribbon Hats, of which the following is a specification, reference being had to the accompanying drawing, forming part thereof.

Fig. 1 is a perspective view of a woven ribbon hat showing my new design.

Fig. 2 is a top plan view.

I claim:

The ornamental design for a woven ribbon hat, substantially as shown.

SAMUEL SCHEUER.
